UNITED STATES PATENT OFFICE.

ARTHUR J. VANCE, OF PAINESVILLE, OHIO.

DRIER FOR SHEET MATERIALS.

Original application filed August 1, 1924, Serial No. 729,617. Divided and this application filed January 15, 1925. Serial No 2,593.

This invention relates to driers for veneers and the like wherein the material under treatment is conveyed through the drier by means of a series of pairs of conveyor rolls, the air in the drier being suitably heated and, in treating some materials, having steam mixed therewith and the application is a division of my copending application for patent on drier for sheet material filed August 1, 1924, Serial Number 729,617.

Metal rolls are frequently used for these conveyor rolls but certain materials are apt to be damaged by direct contact with such metal rolls and it has been proposed to use felt covered rolls for such cases. Such rolls, especially in cases in which the material itself is quite moist or in which steam is used, tend quickly to mat down and become hard and thus become ineffective in operation.

The principal object of the present invention is to provide an improved arrangement of such rolls in connection with a heating device wherein the elements are so disposed that the rolls will lie in juxtaposition to the heating device and are subjected throughout their lengths to heat therefrom, thus being kept sufficiently hot to evaporate any moisture as quickly as it is absorbed. The felt has a great capacity for absorbing moisture and rapidly extracts the moisture from the material at the points of contact as the rolls revolve, the felt then giving up its moisture to the currents of warm air rising from the steam coils. This action ensures the rapid drying of materials that are saturated with moisture, such as plaster board and the like, and ensures the more rapid drying of materials that must be dried in comparatively low temperatures.

One arrangement for accomplishing this object will now be specifically described, particularly pointed out in the appended claims and illustrated in the drawings forming part of this specification wherein:

Figure 1 is a side elevation of a portion of the interior conveyor and heater structure of a drier embodying this invention.

Figure 2 is an enlarged cross section partly broken away, the section being taken on the line 2-2 of Figure 1.

Figure 3 is a section on the line 3-3 of Figure 2.

Any suitable form of construction may be used to support the conveyor rolls. For in-

stance, a conveyor frame may be constructed having vertical members 10 connected by angle irons 11 whereon are supported the return bends 12 of a continuous heater pipe 13 extending back and forth from one angle 60 iron to the other.

Also, between the vertical members 10, extend the bearer bars 14 which support the conveyor rolls. These bars have each a lower series of openings 15 and an upper series of slots 16, each slot being disposed directly above a respective opening. In the lower openings are received the journals 17 of the lower rolls while the upper slots receive the journals 18 of the upper rolls. The journals 17 are preferably fitted in roller bearings 19 and are connected, at one side of the supporting frame work, to the upper journals 18 by gears 20. On the other side each journal 17 is equipped with a sprocket 21 for engagement by a drive chain (not shown).

Each of the rolls has a tubular body portion 22 and is covered by a tubular felt casting 23 and it will be noted that the respective pairs of rolls lie vertically above the space between two adjacent lengths of the heater pipes and that these pipes are very close to the lower rolls. Thus the convection currents rising from these pipes sweep over the rolls and heat them to such an extent that any moisture taken up by the felt coverings during operation is almost instantly caused to evaporate therefrom and accordingly the coverings are maintained in practically dry condition and do not mat nor become hard and slippery.

Changes in the particular manner of supporting the rolls and heater and other changes will readily suggest themselves to those skilled in the art, such changes being entirely within the scope of the invention. Accordingly, it is not desired to confine the invention to the exact form shown and described but rather it is desired to include all such as properly come within the scope 100 claimed.

Having thus described the invention, what is claimed as new, is:

A drier of the type described, comprising a drying chamber, pairs of conveyor rolls 105 aligned longitudinally of the drier, so that the material to be dried may pass between the rolls of each pair, said rolls being provided with an absorbent covering to thereby extract moisture from material passing there-

through and the rolls of each pair being substantially in vertical alinement, means for driving said rolls, and individual moisture-expelling means for each pair of rolls comprising heating means positioned below and closely adjacent to each pair of said moisture-extracting rolls to concentrate heat

thereon and cause convection currents of air to pass up over the rolls to thereby continuously condition the rolls for absorption by 10 causing rapid evaporation of the extracted moisture.

In testimony whereof I affix my signature.
ARTHUR J. VANCE.
